UNITED STATES PATENT OFFICE.

NORMAN BRUCE MILLER, OF NEW YORK, N. Y.

PACKING FOR PISTON-RODS, PLUNGERS, PISTONS, &c.

1,313,320.

Specification of Letters Patent. Patented Aug. 19, 1919.

Application filed July 8, 1918. Serial No. 243,753.

To all whom it may concern:

Be it known that I, NORMAN BRUCE MILLER, residing at New York, in the county and State of New York, have invented certain new and useful Improvements in Packings for Piston-Rods, Plungers, Pistons, &c., of which the following is a specification, said application being for the most part a continuation of pending application Serial No. 224,676, filed March 25, 1918.

This invention relates to a packing for piston rods, plungers, pistons, etc., and the object of this invention is to provide a packing which may be easily and cheaply manufactured, which will be durable, and which will be more uniformly effective than packings heretofore used.

A further object is to provide a packing of such construction that when in use the entire mass thereof will tend to spread out in fan-like fashion under the pressure of steam, or the like, endeavoring to pass the packing.

A further object is to provide a packing which will satisfactorily serve its purpose whether the packing be placed in the stuffing box in either one of two different positions relative to the direction of pressure.

A further object is to provide a packing made up of two halves with a resilient cushion between them, all connected as a single heterogeneous mass.

A further object is to construct the halves so that, when pressure is applied in use, the component parts of the halves tend to spread out in fan-like fashion, the resilient cushion between the halves serving to facilitate such spreading and thereby holding the outer surfaces of the halves tightly in engagement with the opposing surfaces of the shaft and stuffing box.

A further object is to so construct the packing that the halves thereof will be effectively held against possible slipping relative to each other in use.

Other objects and aims of the invention, more or less specific than those referred to above, will be in part obvious and in part pointed out in the course of the following description of the elements, combinations, arrangements of parts and applications of principles constituting the invention; and the scope of protection contemplated will be indicated in the appended claims.

In the accompanying drawings which are to be taken as a part of this specification,

and in which I have shown merely a preferred form of embodiment of the invention:-

Figure 1 is a transverse sectional view, partly in perspective, of a packing constructed in accordance with this invention.

Fig. 2 is a similar view illustrating a modification.

Fig. 3 is a transverse sectional view through a stuffing box showing the packing of Fig. 1 positioned therein as in use.

Fig. 4 is a view similar to that shown in Fig. 3 but illustrating the packing arranged in a different position within the stuffing box, and

Fig. 5 is a view similar to that shown in Fig. 1, but showing the halves of the packing separated to receive the resilient cushion between them.

Referring to the drawings, and particularly to Figs. 1, 3, 4 and 5, for describing in detail the structure which is illustrated therein, the reference characters L and G indicate the two halves of the packing. The reference character H indicates the resilient cushion positioned between the halves L and G.

The halves L and G are each of a laminated construction, being made up of alternate layers of relatively stiff material 1, such as canvas or the like, and relatively resilient material 2, such as rubber or the like.

The material 1 may be either a close woven, or a loose woven, fabric, it may be either of wire, cotton, or asbestos, or other suitable like material, or it may be sheet metal, perforated or otherwise.

The material 2 may be any composition of rubber, or the like, and it is preferably of a consistency such that it adheres to the material 1 and combines the whole into a single heterogeneous mass.

In a structure in which the material 1 consists of canvas, and the material 2 consists of rubber vulcanized into and between the layers of canvas, a very desirable and effective result is obtained.

As clearly seen in Fig. 1, the layers or laminations are given an angular disposition, the laminations of the two halves extending in planes substantially at right angles to each other and converging in the plane of the cushion H.

The line of convergence between the layers of the two halves thus occupies a plane substantially midway between and approxi-

mately parallel to the top and bottom flat surfaces of the body. The materials forming the layers throughout the greater portion of the body are of uniform width, that is, they extend from the cushion H to the top and bottom surfaces of the body (or are continuous between the top and bottom surfaces of the body as in Fig. 2). In addition, there are layers at the right and left hand sides of the body which are of successively decreasing width disposed to complete the rectangular contour of the body.

The material forming the layers in all cases continues uninterruptedly through the exterior surface of the body so as to constitute the friction, or like, surface to engage the shaft or the wall of the stuffing box.

The cushion H is made up of material similar to that above described for the material 2. Also, like the material 2, it preferably consists of rubber suitably vulcanized to the halves L and G so as to combine the whole into a single structure, the cushion serving in this respect as a kind of cement for this purpose.

Viewing Fig. 1, squeezing action in a horizontal direction will spread the laminæ so that the angle defined between the laminæ of the two halves will become more obtuse uniformly throughout the entire mass and the thickness of the packing from top to bottom will be thereby increased uniformly throughout.

Squeezing pressure in a vertical direction in said figure, will reduce the angle and cause the mass of the packing to spread in a horizontal direction.

In use the packing, constructed as just described, is arranged within the stuffing box, as shown in Fig. 3, the diverging laminæ being preferably disposed in the direction from which steam, or the like pressure is exerted. In Fig. 3 this pressure is exerted upon the right hand end, as 3, of the packing, as indicated by the arrows. The pressure is resisted by engagement of the packing with the gland 4. The result is that the pressure of the steam at the end 3 causes the diverging laminæ to spread fan-like substantially uniformly throughout the entire mass of the packing, and to thereby engage more firmly with the opposing walls of the shaft and stuffing box. This is due to the fact that, as the laminæ spread, or tends to spread, the packing tends to become thicker, the resilient material 2, and the somewhat resilient nature of the material 1, readily permitting all necessary desirable spreading. The cushion H is compressed between the halves of the packing, that is, between the converging ends, or edges of the laminæ, and in turn exerts its pent-up force against the laminæ to urge them against the walls of the shaft and box.

While it is, of course, desirable that the packing be positioned so that the pressure is applied at the end thereof, as 3, where the laminæ diverge, nevertheless application of steam pressure at the opposite end, as 4, while not producing quite as satisfactory a result, nevertheless will cause a positive spreading out of the laminæ and thereby effect a tight closure.

As shown in Fig. 4, the packing may be positioned with the diverging laminæ all directed toward the shaft. This arrangement is quite effective. The steam pressure against the surface 5, being resisted by the gland surface 6, causes the various layers of the packing to squeeze together and thereby to make the angular relation of the laminæ of the several groups more acute, thus forcing the packing more tightly against the opposing walls of the shaft and box.

In order to prevent any possible creepage of one of the halves, as L, of the packing, relatively to the other half, as G, when the packing is in use, the opposing surfaces of the halves are preferably formed with longitudinally extending mating corrugations, as 7 and 8, which, pressing against the opposite surfaces of the cushion H, cause the cushion to, in turn, become corrugated. The layers of canvas, or the like, as 1, in each of the halves, preferably extend one into each of the raised portions of the corrugations, as clearly seen in Fig. 5, so that said raised portions are reinforced and are caused to embed themselves into the cushion H and relatively into the depressed portions of the corrugations of the opposite half, when excessive pressure is applied. All likelihood of creepage is thus effectually avoided.

The modification Fig. 2 illustrates a packing which operates upon the same principle as that above described and which may be used in precisely the same way. In this modification the laminæ are given substantially the same angular disposition as in the structure already described but they are made continuous through the center of the packing and the cushion H is omitted. In many respects this packing is as effective and satisfactory as that above described.

It should be added that, where necessary, one or more layers of the fabric, or rubber, or both, may be peeled off when it is desired to more or less alter the contour of the packing to accommodate it to stuffing boxes of different shapes. This is very important, as the efficiency of a packing depends materially upon the fit thereof within the packing box.

As many changes could be made in this construction without departing from the scope of the invention as defined in the following claims, it is intended that all matter contained in the above description or shown

in the accompanying drawings, shall be interpreted as illustrative only and not in a limiting sense.

Having thus described my invention, what I claim as new and desire to secure by Letters Patent is:—

1. A packing comprising a body rectangular in cross section made up throughout of alternate layers of relatively stiff and relatively resilient material, said layers continuing through opposite exterior surfaces of the body and said layers at one side of the body being disposed in convergent relation to the layers at the opposite side of the body.
2. A packing comprising a single heterogeneous body rectangular in cross section and being made up of two halves each of rectangular cross sectional contour, said halves being of resilient material and having a plurality of relatively stiff members embedded therein distributed substantially uniformly throughout the mass thereof and disposed all of said members of one half in convergent relation to all of said members of the other half.
3. A packing comprising a single heterogeneous mass made up of two halves, each of rectangular cross section, each half consisting throughout of a plurality of alternate layers of rubber and fabric, the layers of the two halves being arranged in convergent relation to each other, and a rubber cushion disposed between the halves and being connected thereto for holding the halves together to complete a body rectangular in cross section for use in the manner set forth.
4. A packing made up of two halves, each half consisting throughout of a plurality of alternate layers of rubber and fabric, the layers of the two halves being arranged in convergent relation to each other, the adjacent surfaces of the two halves being roughened, and means connecting said roughened surfaces together.
5. A packing made up of two halves, each half consisting throughout of a plurality of alternate layers of rubber and fabric, the layers of the two halves being arranged in convergent relation to each other, the adjacent surfaces of the two halves being rough-

ened, and a cushion member being received between and connected to said roughened surfaces to hold said halves together.

6. A packing made up of two halves, each half consisting throughout of a plurality of alternate layers of rubber and fabric, the layers of the two halves being arranged in convergent relation to each other, the adjacent surfaces of the two halves being corrugated and having the fabric extending into the raised portions of the corrugations to reinforce said raised portions, together with means connecting said corrugated surfaces together.

7. A packing made up of alternate layers of suitable material, the layers being arranged in an angular disposition and being connected together in a manner so that one or more layers thereof may be peeled off to alter the exterior contour of the packing.

8. A packing comprising a single heterogeneous body rectangular in cross section and being made up throughout of alternate layers of different materials, said layers at one side of the body being disposed in convergent relation to the layers at the opposite side of the body with the line of convergence extending substantially parallel between opposite sides of the body, the layers being of substantially uniform width throughout the greater portion of the body and there being layers of successively decreasing width disposed to complete the rectangular contour of the body.

9. A packing comprising a single heterogeneous body rectangular in cross section and being made up of two halves each of rectangular contour, a cushion disposed between said halves and connected thereto, said halves each consisting of alternate layers of different materials, the layers being of substantially uniform width throughout the greater portion of each of said halves, there being layers of successively decreasing width disposed to complete the rectangular contour of each half, and the layers of said two halves being disposed in convergent relation to each other.

In testimony whereof I affix my signature in the presence of two witnesses.

NORMAN BRUCE MILLER.
